UNITED STATES PATENT OFFICE.

LAMPERT BEMELMANS, OF MIAMI, FLORIDA.

DESIGN FOR A NUTCRACKER.

Application filed October 1, 1928. Serial No. 28,341. Term of patent 3½ years.

To all whom it may concern:

Be it known that I, LAMPERT BEMELMANS, a citizen of the United States, residing at Miami, in the county of Dade and State of Florida, have invented a new, original, and ornamental Design for a Nutcracker, of which the following is a specification, reference being had to the accompanying drawing, forming part thereof.

I claim:

The ornamental design for a nutcracker as shown.

LAMPERT BEMELMANS.
